UNITED STATES PATENT OFFICE

LESTER E. PERRINE, OF DETROIT, MICHIGAN, ASSIGNOR TO GENERAL MOTORS RESEARCH CORPORATION, OF DETROIT, MICHIGAN, A CORPORATION OF DELAWARE

AIR VALVE CARBURETOR

Application filed April 16, 1928. Serial No. 270,341.

This invention relates to carburetors of the air-valve type and it is an object of the invention to provide certain new and useful improvements in carburetors of this type.

5 One of the problems encountered in the construction of a carburetor of the air-valve type is that of designing the carburetor so that it will supply to the engine on which it is installed a combustible mixture containing the desired proportions of fuel and air at all speeds of the engine. This problem arises due to the well-known fact that if, what may be termed, a simple carburetor of the air valve type, is so constructed as to supply a combustible mixture containing the desired proportions of fuel and air at a given engine speed and load it will supply too lean or too rich a mixture at other engine speeds and loads. It is, therefore, an object of 10 this invention to provide a carburetor of the air-valve type so constructed that it will supply a combustible mixture containing the desired proportions of fuel and air to the cylinders of the engine on which it is installed under all conditions of engine speed and load.

More specifically, it is an object of this invention to provide a carburetor of the air-valve type provided with a poppet type of air-valve so controlled that the ratio of fuel to air in the combustible mixture supplied to the cylinders of an internal combustion engine may be automatically varied at any predetermined rate as the speed and load of the engine changes. This object can be attained to some extent by substituting for the simple spring, which ordinarily controls the air-valve, a spring so constructed, or a series of springs so arranged, that equal increments of pressure applied to it or them will cause different deflections thereof. Either of these solutions is, however, more or less unsatisfactory and expensive due to the difficulty of obtaining a single spring with the desired deflection characteristics and the difficulty of obtaining and arranging a series of springs to give desired deflection characteristics. I, therefore, prefer to use the means hereinafter described and shown in

the accompanying drawings to effect the desired result.

In the drawings:

Figure 1 is a side elevation of my carburetor installed on an internal combustion engine.

Figure 2 is a longitudinal section through the carburetor taken on the line 2-2 of Figure 3.

Figure 3 a section on the line 3-3 of Figure 2.

Referring to the drawings, the reference character 10 indicates an internal combustion engine which is provided with an intake manifold 11 having a riser 12 to which is secured the riser 13 of my carburetor 14.

The carburetor includes a float chamber 15 to which fuel is supplied through the pipe 16 and which is open to the atmosphere at 17. The level of the fuel within the float chamber is maintained constant by the float 18 through any suitable mechanism, such as that indicated at 19. Above the float chamber is located an air conduit 20 which includes the riser 13 in which is located the throttle valve 21 which is adapted to be operated by an arm 22. Within the conduit, adjacent the riser end, there is located a mixing venturi 23 into which extends the jet 24 which opens at its opposite end into the float chamber below the fuel level thereof.

Adjacent its end opposite the riser, there is provided in the upper wall of the conduit 20 an air inlet opening 25 which is controlled by a valve 26 provided with a stem 27, extending through the lower wall of the conduit into the float chamber. At a point distant from the valve stem 27 there is provided a bushing 28 which is threaded through the upper wall of the float chamber and on which is threaded a lock-nut 29. Slidably mounted in the bushing 28 and provided at its lower end with a circumferential flange 30 which is adapted to limit the upward movement thereof with respect to the bushing is a shaft 31 which may be operated from the dash of the vehicle through any suitable mechanism. The lower end of the shaft 31 is hollow, as indicated at 32, and in this bore 32 is slidably mounted a rod 33 which carries, adjacent its

lower end, a washer 34 seated on a pin 35. Surrounding the portion of the rod 33 between the flange 30 and the washer 34 is a coil spring 36 which bears at its opposite ends against the flange and washer, urging the rod 33 downwardly.

Secured to the upper wall of the float chamber by the flanges 37 is a channel-shaped member 38, the upper surface of whose web is shaped to provide a cam surface 39. Extending through the channel of the member 38 and fulcrumed on the cam surface 39 is a lever 40 through which and the vertical slots 41 in the flanges 37 extends a pin 42 which prevents movement of the lever lengthwise of the member 38. The lever 40 is pivoted at its opposite ends to the lower end of the rod 33 and the lower end of the valve stem 27 by the pins 43 and 44, respectively.

In the float chamber directly below the valve stem 27 is provided a dash-pot 45 in which is located a piston 46 to which is secured an upwardly extending rod 47. To the upper end of the rod 47 and to lower end of the valve stem 27 is pivoted, by the pins 48 and 49, respectively, a link 49.

When the throttle valve 21 is opened and the engine cranked the pressure in the conduit 20 is reduced to sub-atmospheric by the suction of the engine. This reduction of pressure in the conduit causes the valve 26 to open against the pressure of the spring 36 and air to flow into the conduit through the opening 25. The air flows through the conduit, a portion of it passing into the venturi 23 and mixing therein with the fuel which has been discharged from the jet 24 due to the reduction of pressure in the conduit. This primary mixture then passes out of the venturi and mixes with the remainder of the air, forming a combustible mixture of the proper proportions which then passes through the intake manifold to the cylinders of the engine.

As has been intimated, if in, what has been termed, simple carburetors of the type described, the spring which resists the movement of the air-valve is adjusted to give the proper fuel-air ratio at a given engine speed the mixture will become too rich or too lean at other speeds and loads. In my carburetor, the fulcrum of the lever 40 shifts upon movement of the air-valve requiring an increasingly greater increase in pressure to open the valve a given amount and, conversely, a decreasingly smaller decrease in pressure to allow the valve to close a given amount as the air valve opens or closes. It is now obvious that, with my arrangement, by a suitable selection of cam shape, the ratio of fuel to air in the combustible mixture supplied to the cylinders of the engine may be automatically varied at any predetermined rate.

The dash-pot, as is obvious, serves to damp the movement—i. e. prevent fluttering—of the air valve. The initial pressure on the

spring 36 may be varied by screwing the bushing 28 up or down and the bushing may be locked in any adjusted position by the lock-nut 29. The engine, it is obvious, may be "choked" by moving the shaft 31 downwardly.

Though I have described and illustrated a specific embodiment of my invention it is to be understood that my invention is not limited thereto but includes all modifications within the scope of the appended claims.

The expression "varied at any predetermined rate", or expressions of like import, used in this specification and the appended claims is to be understood to cover the special case where the rate is zero, i. e. where there is no variation.

I claim:

1. In a carburetor, a passage through which air is adapted to flow to the cylinders of an internal combustion engine, a valve for controlling the flow of air through the passage, a spring for resisting the opening of the valve, and means for transmitting the movement of the valve to the spring including a lever having a varying fulcrum.

2. In a carburetor, a passage through which air is adapted to flow to the cylinders of an internal combustion engine, a valve for controlling the flow of air through the passage, a spring for resisting the opening of the valve, and means including a lever fulcrumed on a cam surface for transmitting the movement of the valve to the spring.

3. In a carburetor, an air passage, a fuel nozzle projecting into the air passage, a valve for directly controlling the admission of air into the air passage and the flow of air past the fuel nozzle, and means adapted to oppose at a variable rate increasing resistance to the opening of the valve.

4. In a carburetor, an air passage, a fuel nozzle projecting into the air passage, a valve for directly controlling the admission of air into the air passage and the flow of air past the fuel nozzle, and means adapted to oppose at a predetermined variable rate increasing resistance to the opening of the valve.

5. In a carburetor, an air passage, a fuel nozzle projecting into the air passage, a valve for directly controlling the admission of air into the air passage and the flow of air past the nozzle, means including a spring device to oppose at a variable rate increasing resistance to the opening of the valve, and means for varying the initial stress on the spring device.

6. In a carburetor, an air passage, a fuel nozzle projecting into the air passage, a valve for directly controlling the admission of air into the air passage and the flow of air past the nozzle, means adapted to oppose at a variable rate increasing resistance to the opening of the valve, and means whereby the

valve may be closed against the pressure of the air flowing thereby.

7. In a carburetor, an air passage, a fuel nozzle projecting into the air passage, a valve for directly controlling the admission of air into the passage and the flow of air past the nozzle, means adapted to oppose at a variable rate increasing resistance to the opening of the valve, and means for damping the movement of the valve.

10 8. In a carburetor, an air passage, an opening through which fuel is adapted to be discharged into the air passage, a valve for directly controlling the admission of air into the air passage and the flow of air past the opening, and means adapted to oppose at a continuously variable rate increasing resistance to the opening of the valve.

20 9. In a carburetor, an air passage, an opening through which fuel is adapted to be discharged into the air passage, a valve for directly controlling the admission of air into the air passage and the flow of air past the opening, and means, including a spring and 25 means operatively interposed between the spring and the valve, adapted to oppose at a variable rate increasing resistance to the opening of the valve.

In testimony whereof I affix my signature.
